CIGARETTE LIGHTER

William Retzler, Wickham, England, assignor to
Tetra Moletric Limited

Continuation-in-part of design application Ser. No. 12,972,
July 26, 1968. This application Aug. 4, 1969, Ser. No.
18,765

Claims priority, application Great Britain Feb. 16, 1968

Term of patent 14 years

Int. Cl. D27—05

U.S. Cl. D48—27

Fig. 1.

Fig. 2.

Fig.3.

Fig.4.

Fig. 5.

Fig. 6.

Fig.7

Fig.8

Fig.9

FIG. 1 is a perspective view of a cigarette lighter embodying my new design, showing the lighter in closed position.

FIG. 2 is a side elevational view thereof, the opposite side being identical.

FIG. 3 is a perspective of a second embodiment of my new design, showing the lighter in closed position.

FIG. 4 is a side elevational view thereof, the opposite side being identical.

FIG. 5 is a perspective view of a third embodiment of my design, showing the lighter in closed position.

FIG. 6 is a side elevational view thereof, the opposite side being identical.

FIGS. 7, 8 and 9 are perspective views of the embodiments of FIGS. 1, 3 and 5 respectively, showing the lighter in igniting position.

The bottom of the lighter is flat and unornamented.

This is a continuation-in-part of design application Ser. No. D. 12,927, filed July 26, 1968 and now abandoned.

I claim:

The ornamental design for a cigarette lighter, as shown and described.
